UNITED STATES PATENT OFFICE.

CHARLES B. COLLINS, OF BENTLEY, KANSAS.

GRAIN DOOR.

Application filed February 9, 1926. Serial No. 87,988.

My present invention has to do with grain doors for cars; and it contemplates the provision of a grain door of such construction that the loss of grain is averted and this notwithstanding that my novel grain door is susceptible of being placed in and removed from a car without the use of tools and without the employment of nails, screws or other extraneous means.

10 The invention also contemplates the provision of a grain door construction of such character that it will be at all times associated with and form a part of the car.

15 The invention further contemplates the provision of a grain door construction adapted for use in conjunction with large openings such as are provided in what are known as automobile cars, the construction being braced in such manner as to render it feasible for use in conjunction with large openings, and being characterized by means whereby the car may be expeditiously unloaded without the removal of the superposed grain door sections.

20 25 Other objects and practical advantages of the invention will be fully understood from the following description and claims when the same are read in connection with the drawings, accompanying and forming part of this specification, in which:—

Figure 1 is a side elevation taken from a view point outside of a car body and illustrating the best practical embodiment of my invention of which I am cognizant.

30 35 Figure 2 is an elevation, partly in section, taken from a view point within the car body.

Figure 3 is an enlarged vertical transverse section taken in the plane indicated by the line 3—3 of Figure 1.

40 Figure 4 is a horizontal section.

Figure 5 is a perspective showing a portion of one of the superposed door sections.

Figure 6 is a fragmentary or detail perspective showing the skeleton section that is arranged below and in the same plane as the major portion of the superposed door sections.

Figure 7 is a detail elevation showing the swingable retainer for normally preventing upward movement of the supplementary door sections back of the said skeleton section.

50 55 Similar numerals of reference designate corresponding parts in all of the views of the drawings.

The door opening of the car body 1 is

designated by 2, and the posts at opposite sides of said opening 2 are designated by 3. One of the posts 3 is provided with a guideway 4 at its inner side and the other post 3 is provided with guideways 4 and 4^a at its opposite sides. Manifestly within the purview of my invention the guideways may be formed by channeling the posts 3 as illustrated or by nailing or otherwise fastening strips to the said posts. Within the car body and in spaced relation to the post 3 at the left of Figures 2 and 4, I provide a supplementary post 5, channeled at its inner side as designated by 6; and I also provide above the space between the posts 3 and 5 hooks 7. It will also be noticed by comparison of Figures 2, 3 and 4, that I provide a horizontal rod 8 above the door opening 2 and on the said rod 8 is adjustably mounted 70 a chain section 9. The said chain section 9 serves for the connection to the rod 8 of the upright shiftable post 10 of my novel door structure. The said post 10 is removably arranged at its upper and lower ends in 80 seats designated by 11 and 12, respectively, and is designed when not in use to be removed from the door opening 2 and then after the chain section 9 is moved longitudinally on the rod 8, to be removably placed 85 in substantially horizontal position on the hooks 7 so as to be out of the way and yet within convenient reach for use when desired. The said supplementary post 10 constitutes an important feature of my invention 90 as will be appreciated when it is stated that by reason of the supplementary post 10, it is feasible for my novel door to be used in conjunction with the comparatively large openings such as are provided in what are known as automobile cars. The post 10 manifestly will so brace the door structure that the said structure may be used in conjunction with a large opening, and hence it will be understood that automobile cars may 95 when deemed expedient be used for the transportation of grain.

The lower portion of the post 10 is reduced as designated by 13 and best shown in Figures 3 and 7, the said reduced portion 13 affording a space 14 at the inner side of the post 10 to permit of manipulation of the supplementary door section 15 and the retainer 16 for use in conjunction with said supplementary door section 15. The retainer 16 is pivoted at 17, Figure 3, to the supplementary post 10, and is swingable 110

and is adapted when in the position shown in Figures 1, 3 and 7 to hold the supplementary imperforate section 15 against upward movement. When, however, the said retainer 16 is swung in either direction to a substantially horizontal position, it will be manifest that the supplementary door section 15 may be readily raised in the space 14 of post 10 and the spaces 14* of posts 3 so as to permit grain to flow through the opening of the skeleton section 18, and this without disturbing the vertical series of door sections 19 which are arranged one above the other and in the same plane as the skeleton section 18, Figure 3. The supplementary door section 15 is provided at its outer side with projections 20, Figure 1, the said projections 20 being provided in order that a crowbar or the like may be conveniently used for the raising of the supplementary door section 15 when it is desired to permit grain to flow out through the opening in the skeleton section 18. It will also be noticed by comparison of Figures 3 and 6 that the skeleton section 18 is provided with a flange 21 which is designed to receive the lower edge portion of the supplementary door section 15 and hold said door section 15 to the skeleton section 18 and against lateral movement, with a view to contributing to the strength of the lower portion of the door. Each of the door sections 19 is provided with a pendant flange 22 adapted to lap over the upper portion of the next lower door section 19, Figure 3. I would also have it understood that the door sections 19 are removable from the upper ends of the guideways 4 in the posts 3, and when not in use the said door sections 19 are arranged one above the other in the channels 4* and 6 of posts 3 and 5, respectively, so as to be entirely out of the way and yet carried in and by the car in such manner that when it is desired to place the said door sections 19 in position to control the door opening 2, the same may be expeditiously and easily accomplished.

When the parts of my novel grain door are positioned as shown in Figures 1, 2 and 3, and it is desired to bring about the discharge of grain from the car body 1 without disturbing the door sections 19, it is simply necessary for an operative to move the retainer 16 in one direction or the other to a substantially horizontal position, and raise the door section 15 through the medium of a crowbar or other appropriate instrument applied to the projections 20. When this is done the door section 15 will uncover the opening in the skeleton section 18, and the grain may pass through the said opening in section 18.

It will also be readily understood from the foregoing that when it is not desired to use my novel grain door construction, the post

10 may be placed upon the hooks 7, and the other sections of the door may be placed between one post 3 and the post 5 and in the opposed channels thereof, and consequently all of the elements of the grain door structure will be entirely out of the way so far as the door opening 2 is concerned, and yet will be carried in neat fashion in the interior of the car body where they will be adequately protected and yet will not interfere in any appreciable measure with the use of the car body for the carriage of freight other than grain.

It will also be understood from the foregoing that the different parts of my improvement may be formed of wood or metal or some of the parts may be formed of wood and others of metal without affecting my invention.

Notwithstanding the practical advantages ascribed to my novel door construction, it will be appreciated that the construction is simple and inexpensive and all of its parts are susceptible of ready manipulation.

I have entered into a detailed description of the construction and relative arrangement of the parts embraced in the present and preferred embodiment of my invention in order to impart an exact understanding of said embodiment. I do not desire, however, to be understood as limiting myself to the precise construction and relative arrangement of elements as illustrated, my invention being defined by my appended claims within the scope of which changes in structure and in arrangement may be made without departure from my invention.

Having described my invention, what I claim and desire to secure by Letters-Patent, is:—

1. In a grain door construction and in combination, posts at opposite sides of a door opening and having opposed guides, a supplementary post arranged intermediate of and spaced from the first-named posts and having a reduced lower portion, a swingable retainer connected to the said reduced lower portion of said intermediate post, a vertically movable supplementary door section arranged below said retainer and in the guides of the first-named posts and movable vertically when the retainer is swung in one direction or the other, a skeleton door section arranged at the inner side of the said supplementary door section, and superposed removable door sections arranged in the guides of the first-named posts and above the skeleton door section.

2. In a grain door construction, posts at opposite sides of a door opening and having opposed guides, a supplementary post arranged intermediate of and spaced from the first-named posts and having a reduced lower portion, a swingable retainer connected to the said reduced lower portion of said

intermediate post, a vertically movable supplementary door section arranged below said retainer and in the guides of the first-named posts and movable vertically when the retainer is swung in one direction or the other, a skeleton door section arranged at the inner side of the said supplementary door section, and superposed removable door sections arranged in the guides of the first-named posts and above the skeleton door section, with a substantially horizontal rod disposed above the door opening, a flexible connection between said rod and the intermediate removable post, said flexible connection movable longitudinally on the rod, hooks in the car body and at one side of the door opening to support said intermediate post when idle, and a supplemental post arranged in the car body and spaced from one of the first-named posts and adapted to serve in conjunction with said post in retaining the door sections when the same are not in use.

3. In a grain door and in combination, posts at opposite sides of a door opening, an intermediate post, a skeleton door section arranged and movable in said posts and having an opening, a vertically movable door section arranged in said posts and normally closing said opening and movable vertically in a plane alongside that of the skeleton door section, and movable means adapted in one position to hold the supplementary door section against upward movement and in another position to permit of upward movement of said supplementary section.

carried by one post and adapted in one position to hold the supplementary door section against upward movement and in another position to permit of upward movement of said supplementary section. 35

4. In a grain door and in combination, posts at opposite sides of a door opening, an intermediate post, a skeleton door section 40 arranged and movable in said posts and having an opening, a vertically movable door section arranged in said posts and normally closing said opening and movable vertically in a plane alongside that of the skeleton door section, and movable means adapted in one position to hold the supplementary door section against upward movement and in another position to permit of upward movement of said supplementary section; 45 the said intermediate post having a reduced lower portion, and the said means for preventing upward movement of the supplementary door section being in the form of a retainer pivotally connected to said reduced portion of the intermediate post, and the said supplementary door section being provided at its outer side with projecting means 50 for use in conjunction with a crowbar or the like used in lifting the supplementary door section. 55

In testimony whereof I affix my signature.

CHARLES B. COLLINS.
